LUG STRAP SUPPORT FOR TEXTILE LOOMS

Wingo Herron, Charlotte, N. C.

Application June 23, 1948, Serial No. 34,679

2 Claims. (Cl. 139—154)

1

This invention relates to a lug strap support for textile looms.

It is an object of the present invention to eliminate wear and breakage of the lug strap hanger on looms and wherein the use of screws or other like fastening elements on the picker stick are unnecessary.

Other objects of the present invention are to provide a lug strap support which is of simple construction, easy to assemble upon the picker stick, strong, compact and durable, inexpensive to manufacture and efficient in operation.

For other objects and for a better understanding of the invention, reference may be had to the following detailed description taken in connection with the accompanying drawing, in which

Fig. 1 is a side elevational view of a picker stick with the lug strap support of the present invention assembled thereon.

Fig. 2 is an elevational view, in section, taken on line 2—2 of Fig. 1.

Fig. 3 is a transverse sectional view taken on line 3—3 of Fig. 1.

Fig. 4 is an elevational view of the clamping plate.

Fig. 5 is a sectional view taken on line 5—5 of Fig. 4.

Fig. 6 is a rear elevational view of the eye or open frame unit.

Fig. 7 is a vertical sectional view of the open frame taken on line 7—7 of Fig. 6.

Referring now to the figures, 10 represents a picker stick which has to be connected to an operative part 11 of a loom. An eye or frame 12 is placed on the front of the stick 10 and a leather or flexible strap 13 is extended about the stick and through the eye 12. A piece of material as indicated at 14 is placed in the bight of the strap. The ends of the strap 13 are connected by a clamp 15 to the part 11. A bolt 16 extends through the part 11 and through the clamp 15. The part 11 may have an elongated slot 17 in order to permit the adjustment of the strap on the part 11.

The eye frame has a rectangular opening 18 through which the strap 13 extends and has guide recesses 19 and 20 vertically spaced from one another on its inner face to receive the picker stick 10. The eye frame 12 further has a projection 22 with vertically aligned pads 23 which will abut a wear plate on the outer edge of the picker stick. The projection 22 is sufficiently wide to provide stove bolt openings 24 and 25 on the opposite sides of the pads 23.

2

On the inner edge of the stick 10 there is disposed a clamping plate 27 having ears 28 with bolt openings 29 therein for receiving clamping bolts 31. This clamping plate is similarly provided with pads 32 and 33 which abut the inner edge of the stick. With the provision of pads both on the eye 12 and on the clamping plate 27 a better engagement of the same is made with the stick and the eye and clamping plate will each be certain to have a two-point connection with the wear plate and picker stick edge, respectively.

It will be noted that the pads are provided on the opposite sides of the clamping plate 27 so that the clamping plate can be reversed should the wear have been too great on the one side.

On the outer edge of the stick, between it and the eye 12, is a strap or wear plate 34. The pads 23 of the projection 22 of eye 12 will engage the wear plate 34.

While various changes may be made in the detail construction, it shall be understood that such changes shall be within the spirit and scope of the present invention as defined by the appended claims.

I claim:

1. A loom lug strap support for supporting a bight portion of a flexible strap the ends of which are connected to an operating part of a loom, said support comprising: an open frame element through which the bight portion of the strap may extend, said open frame element having a projection with vertically spaced pads thereon; a wear plate adapted to abut said pads and to engage an edge of a picker stick; said projection having openings; bolts extending through said openings; a clamping plate having vertically spaced pads for engagement with the opposite edge of said picker stick, said clamping plate having openings to receive said bolts; said open frame element having recesses for receiving the wear plate and the picker stick; and a filler piece adapted to be received within the bight portion of said strap.

2. A loom lug strap support for supporting a bight portion of a flexible strap the ends of which are connected to an operating part of a loom, said support comprising: an open frame element through which the bight portion of the strap may extend, said open frame element having a projection with spaced pads thereon; a wear plate adapted to abut said pads and to engage an edge of a picker stick; said projection having openings; securing elements extending through said openings; a clamping plate having spaced

pads for engagement with the opposite edge of said picker stick, said clamping plate having openings to receive said securing elements; said open frame element having recesses for receiving the wear plate and the picker stick; and a filler piece adapted to be received within the bight portion of said strap.

5 WINGO HERRON.
